UNITED STATES PATENT OFFICE.

ELIAL M. STAPLES, OF ELIZABETH, NEW JERSEY, ASSIGNOR TO THE SINGER
MANUFACTURING COMPANY OF NEW JERSEY.

THREAD-TENSION-RELEASING DEVICE FOR SEWING-MACHINES.

SPECIFICATION forming part of Letters Patent No. 484,002, dated August 12, 1890.

Application filed May 16, 1890. Serial No. 352,025. (No model.)

To all whom it may concern:

Be it known that I, ELIAL M. STAPLES, a citizen of the United States, residing at Elizabeth, in the county of Union and State of New Jersey, have invented certain new and useful Improvements in Sewing-Machine Tension-Releases, of which the following is a specification, reference being had therein to the accompanying drawings.

10 My invention relates to that class of tension-releasing devices operated from the presser-foot lifter when the presser-foot is raised from the work, the object of my invention being to provide a tension-release of this character 15 which may be applied to sewing-machines as at present constructed without changing any of the parts of the tension device. To this end I provide the face-plate of the machine with a hole in which is loosely fitted a sliding 20 pin, the rear tapered or rounded end of which projects into the path of the lifting-lever when the latter is raised, and the forward end of which is provided with a flange arranged to engage the outer tension disk or plate and 25 force it away from its co-operating bearing-surface, thus leaving the thread free to be drawn through the tension device.

In the drawings, Figure 1 is a front view of the face-plate or head of the sewing-machine provided with my invention. Fig. 2 is 30 a partial rear view of the same. Fig. 3 is a detailed section. Fig. 4 is a detail illustrating a slightly-modified form of my invention.

The tension device herein shown consists 35 of an ordinary pair of tension-disks 2 mounted on a pin 3, the outer of said disks being pressed upon by a spring 4, and the latter being held upon said pin by the regulating-nut 5. Closely adjacent to the periphery of 40 said tension-disks the face-plate 6 is provided with a hole, in which is loosely fitted a sliding pin 7, the rear end of said pin being preferably tapered or rounded, as shown, and the forward end of said pin being provided with 45 a flange or lip 8, which is in contact with the outer tension-disk. The said pin is so arranged that its inner tapered or rounded end

is in the path of movement of the cam of the presser-foot-lifting lever 9, so that when the said lever is raised to the position indicated 50 by dotted lines in Fig. 2 the said pin will be pressed outward, as represented in Fig. 3, so as to tilt or force outward the outer tension-disk and thus release the thread from the pressure thereof.

Instead of tapering or rounding the inner end of the pin 3, it is obvious that the said end may be square or beveled, and the presser-foot lifter may also be beveled, all as shown in Fig. 4.

I am aware that it is not new, broadly, to release or lift the outer tension-disk from its co-operating disk or friction-surface by means of a horizontally-sliding pin operated by the presser-foot lifter; but in the devices of this 65 character as heretofore made some special construction of the tension device different from that usually employed was required. My improved tension-releasing device may be applied to sewing-machines now in use simply by boring a hole in the face-plate adjacent to the tension device and placing in the hole the sliding pin 7, constructed and arranged as herein shown and described.

When the presser-foot is lowered by turning the lifting-lever down to its normal position, as shown by full lines in Fig. 2, the spring 4 instantly restores the outer tension-disk to its operative position, the pressure of the spring, acting through said disk, also forcing the pin 7 inward in position to be acted upon when the lifting-lever is next raised.

I claim—

1. The combination, with a sewing-machine tension device consisting of two disks or 85 plates, a pin on which said disks or plates are mounted, and a spring for forcing the said disks or plates in contact with each other, of a presser-foot-lifting lever and a sliding pin provided with a lip or flange to engage the 90 rim of the outer of said disks or plates and having its inner end arranged in the path of movement of the said lifting-lever when the latter is raised, substantially as set forth.

2. The combination, with the tension-disks, the pin on which said disks are mounted, and the spring for forcing the same together, of the presser-foot-lifting lever and the sliding pin 7 having a rounded or beveled rear end arranged in the path of movement of the said lifting-lever, and provided near its outer end with a flange 8 engaging the inner edge of

the rim of the outer of the said disks, substantially as set forth. 10

In testimony whereof I affix my signature in presence of two witnesses.

ELLAL M. STAPLES. [L. S.]
